DESIGN FOR A DOOR HANDLE OR THE LIKE

Harry I. Strnard, Renton, and Warren J. Myers,
Seattle, Wash.

Application May 27, 1946, Serial No. 130,088

Term of patent 7 years

(Cl. D10—8)

To all whom it may concern:

Be it known that we, Harry I. Strnard and Warren J. Myers, citizens of the United States of America, residing at Renton and Seattle, respectively, in the county of King and State of Washington, have invented a new, original, and ornamental Design for a Door Handle or the like, of which the following is a specification, reference being had to the accompanying drawing, forming part thereof.

Figure 1 is a perspective view, looking at one side of the door handle or the like, and Figure 2 is a perspective view, looking at the same from the opposite side.

We claim:

The ornamental design for a door handle or the like, substantially as shown.

HARRY I. STRNARD.
WARREN J. MYERS.
